UNITED STATES PATENT OFFICE.

FLOYD E. TINKHAM, OF BATAVIA, NEW YORK.

CLOTHES-RACK.

1,174,532.

Specification of Letters Patent. Patented Mar. 7, 1916.

Application filed March 5, 1915. Serial No. 12,439.

To all whom it may concern:

Be it known that I, FLOYD E. TINKHAM, a citizen of the United States, residing at Batavia, in the county of Genesee and State 5 of New York, have invented certain new and useful Improvements in Clothes-Racks, of which the following is a specification.

The object of this invention is to provide a new and useful clothes rack that can be 10 readily adjusted to any height. This and other objects of this invention will be fully illustrated in the drawings, described in the specification and pointed out in the claim at the end thereof.

15 In the accompanying drawings, Figure 1 is a perspective view of the clothes rack. Fig. 2 is a vertical section taken on the line 2^x—2^x of Fig. 1.

20 In the figures like reference numerals indicate like parts.

The clothes rack consists of an upright 1 having the supporting blocks or brackets 2 and 3 fastened to either end thereof. The upright is fastened to the studding of the 25 wall by means of suitable screws fastened through the upright 1 and blocks 2 and 3 respectively. The object of the blocks 2 and 3 is to support the upright 1 at a suitable distance from the wall to allow the support 4 to slide freely up or down thereon. 30 For this purpose the support 4 is provided with a sleeve or socket 5 which surrounds the upright. Suitably spaced apart on the upright 1 are the notches or grooves 6 which 35 are preferably cut into the upright at an angle thereto as shown in both of the figures.

The support 4 is held in place on the upright by means of a spring 7. This spring is pivoted at 8, 8 near the top of the sleeve 40 5 at either side thereof and passes through the top of the support at 9, 9 and down to one of the notches or grooves 6. By passing this spring through the top of the support at a suitable distance from its pivot 8 45 enough tension is put on it to make the end of the spring press against the upright 1 and snap into the notches 6, clamping the support 4 rigidly onto the upright.

When it is desired to raise or lower the 50 support 4 along the upright 1, the spring 7 is pulled out of the groove 6 in which it had been previously placed. This leaves the sleeve 5 free to move up or down and when the desired height is reached the spring is

allowed to snap into the corresponding 55 groove on the upright 1. This arrangement gives the user of this rack a considerable range in the adjustment of its height. This adjustment too is secured in a very simple and easy way and makes out of the whole 60 structure a very neat and easily operated device.

To support the clothes from the rack the bars 9, 9 are provided. These bars are mounted to slide in slots 10, 10 provided in 65 the support 4 as shown in Fig. 1. The bars are preferably made flat and have on one end thereof the hook screws 11 and on the other end the pins 12 fastened therein. The hooks 11 and pins 12 are for the purpose of 70 holding the bars 9, 9 in the support 4. When the bars are not in use they are supported from the rim of the support by means of the hooks 11 while the pins 12 are used for a stop when the bars are pulled 75 out or erected to prevent them from sliding out of the slots 10, 10. To hold the bars horizontally when the clothes are hung on them the flat top 13 of the support 4 is provided. The inner ends of the bars 9, 9 rest 80 against this top which acts as a stop therefore and holds them in a horizontal position, as shown in Fig. 2. When it is desired to fold the bars back against the upright they are lifted on the end and allowed to drop 85 down through the slots of the support until the hooks 11 encounter the rim of the support which stops and holds them in place in inoperative position. To move the bars into operative position the bars are pulled out 90 of the slots 10, 10 until the pins 12 stop them, at which point the bars are allowed to drop into the horizontal or operative position.

I claim:

95
In a clothes rack the combination of an upright, a support having a sleeve integral therewith surrounding said upright, said sleeve being mounted to slide on said upright, a bracket on both ends of said upright 100 to hold said upright away from the wall and prevent said sleeve from sliding out of engagement with said upright, a bow spring having its ends rigidly fastened in the opposite sides of said sleeve, said support being provided with openings in the top through which the sides of said bow spring pass and by which it is held rigidly in po- 105

sition with its lower end forced against said upright, slots cut across the front of said upright, said spring forming a bail at the bottom thereof to engage said slots to hold said support on said upright and clamp said support rigidly in place thereon, horizontal bars supported from said support.

In testimony whereof I affix my signature in presence of two witnesses.

FLOYD E. TINKHAM.
